(57) CLAIM

The ornamental design for a garment, as shown and described.

DESCRIPTION

FIG. 1 is a front perspective view of a garment showing my new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.

The short evenly spaced broken lines depict stitching which forms part of the claimed design. The long, evenly spaced broken lines that outline the partial human figure assists in illustrating how the garment may appear when in a position of use and forms no part of the claimed design. The short broken lines arranged on the rear side of the garment at the upper center of the garment depicts a feature of the article that forms no part of the claimed design.
